US0D1003644S

(12) **United States Design Patent** (10) **Patent No.:** **US D1,003,644 S**
(45) **Date of Patent:** **** Nov. 7, 2023**

(54) **APPLIANCE**

(71) Applicant: **Sunbeam Products, Inc.**, Boca Raton, FL (US)

(72) Inventors: **Bruce Arnold**, Portage, MI (US); **Rury Vizcarra**, Wyoming, MI (US); **Charlotte Zale**, University Heights, OH (US); **Chris Leyden**, Portage, MI (US)

(73) Assignee: **Sunbeam Products, Inc.**, Atlanta, GA (US)

(**) Term: **15 Years**

(21) Appl. No.: **29/783,995**

(22) Filed: **May 17, 2021**

(51) LOC (14) Cl. **07-01**

(52) U.S. Cl.

USPC **D7/310**

(58) **Field of Classification Search**

(57) **CLAIM**

We claim the ornamental design for an appliance, as shown and described.

DESCRIPTION

FIG. 1 is a left perspective view of a first embodiment of an appliance;

FIG. 2 is a right side elevation view of the first embodiment of the appliance;

FIG. 3 is a left side elevation view of the first embodiment of the appliance;

FIG. 4 is a front elevation view of the first embodiment of the appliance;

FIG. 5 is a rear elevation view of the first embodiment of the appliance;

FIG. 6 is a top plan view of the first embodiment of the appliance;

FIG. 7 is a bottom plan view of the first embodiment of the appliance; and,

FIG. 8 is a right perspective view of the first embodiment of the appliance.

Broken lines shown in the drawing views are included for illustrative purposes only and form no part of the claimed design.
